UNITED STATES PATENT OFFICE.

DAVID S. WILLIAMS, OF PORTLAND, OREGON.

SWIVEL-FRAME FOR RAZOR-STROPS.

1,316,403.

Specification of Letters Patent. Patented Sept. 16, 1919.

Application filed December 27, 1918. Serial No. 268,538.

To all whom it may concern:

Be it known that I, DAVID S. WILLIAMS, citizen of the United States, residing at Portland, in the county of Multnomah, 5 State of Oregon, have invented certain new and useful Improvements in Swivel-Frames for Razor-Strops; and I do hereby declare the following to be a full, clear, and exact description of the invention, such as will 10 enable others skilled in the art to which it appertains to make and use the same.

The present invention relates to improvements in swivel frames for razor strops; and it comprehends, briefly the provision of a 15 device of the general class or character indicated, which possesses the triple advantage of being applicable with equal facility to strops of widely differing thicknesses, of holding the strop, irrespective of its thickness, 20 constantly in the same position and preventing it from swaying sidewise, and of enabling the interchangeable use of swivel rings or hooks of various types.

With the above and other objects in view, 25 the improved device, as preferably constructed, comprises a frame proper which consists of a pair of companion parts or members having lateral flanges which overlie each other so as to form a lap joint, and 30 which fit squarely against the end face of the strop. These two members are detachably clamped together by a bolt or screw, and their overlapping flange portions are provided with mating transverse recesses which 35 open through the free edges thereof and unite in forming a slot or opening in which the stem of the swivel is engaged and is held in place thereby, the arrangement being such that the width of the overlap and, 40 hence, the length of the slot or opening, will vary in accordance with the thickness of the strop.

An embodiment of the invention is illustrated in the accompanying drawing, where- 45 in:

Figure 1 is a fragmental perspective view of a strop equipped with the improved swivel frame;

Fig. 2 is a vertical cross-sectional view 50 thereof on a slightly larger scale;

Fig. 3 is a collective view, showing the several parts of the frame disassembled; and

Fig. 4 shows, by way of example, a type 55 of swivel which may be used in place of the one represented in Figs. 1, 2 and 3.

While the drawing discloses a form of the invention which may be regarded for all present purposes as preferred, it is to be understood that no limitation to the precise structural details comprised in such disclosure is contemplated, since modifications and changes in the construction and arrangement of the component parts of the invention may well be made within the scope of the invention as subsequently claimed.

The strop 1 may be of any approved character, and may consist of any suitable number of sections or members, two of which are represented in the present instance, 70 designated by the numerals 2, 3. These sections (or, in the case of a strop comprising a single section or member, such member itself) may have any desired thickness, thereby varying the total thickness of the strop, 75 as will be understood; but in any event, the strop, whether single or multiplex, will have a flat end face, and will be provided adjacent said face with a transverse hole 4.

The frame 5 comprises a pair of counter- 80 part members 6 and 7, each of which consists of a sheet metal plate having its upper edge bent to form an inwardly-directed, lateral flange 8 or 9. These flanges are provided, in turn, with centrally-located, 85 transverse recesses 10 and 11, which open through the free edges, thereof; and the body of one member, in the present instance the member 6, is provided with a central aperture 12 of circular outline, while that 90 of the other member 7 is formed with a rectangular aperture 13. The upper end of the strop is designed to fit between the two frame members 6 and 7, the flanges of which project toward and overlap each other, so 95 that the frame as a whole may be said to have the shape of an inverted U in cross-section, with the base of the U formed by the slidably related, overlapping flanges. The recesses 10 and 11 register with each other 100 at this time, and unite in producing a single, transverse slot, whose length depends upon the extent of the overlap of the flanges or, in other words, upon the thickness of the strop, the arrangement being such that the 105 slot is closed at one end by the inner end of the recess 11 and at the other end by the inner end of the recess 10. The apertures 12 and 13 register at the same time with the adjacent ends of the hole 4, in order to per- 110

mit the passage of a clamping screw or bolt 14 therethrough, said screw being inserted through the circular aperture 12 in the member 6 and projecting into the threaded bore 5 of a cap or nut 15, the rectangular shank of which fits in the similarly-shaped aperture 13 in the member 7.

The swiveled attaching element 16 is removably connected to the frame, and may 10 have any desired construction or shape. It may be of the type shown in Fig. 3, or of any other preferred type; for example, it may be constituted by the **B**-shaped member 17 illustrated in Fig. 4. It will embody in 15 any instance, however, a stem or stud 18, which is headed at opposite ends, as indicated at 19 and 20, and which fits loosely in an opening provided for it in the base of the ring or equivalent member. The stud 20 18 fits in the slot formed by the mating recesses in the flanges 8 and 9, being positioned in the recess in the flange 8 prior to the coupling of the two members together. The lower head 20 of the stud is thus clamped between the under flange 8 and the end face of 25 the strop, and it preferably fits in a seat 21 formed in the strop end for the purpose of enabling the under flange to abut directly and squarely against the surface of the strop 30 and throughout its entire extent.

In the form of attaching element represented in Fig. 3, there are comprised two opposed, arc-shaped arms 22, which are pivoted in a carrier yoke 23, the latter being 35 formed with the opening in which the stem or stud 18 is engaged. The arms 22 taper slightly, and are arranged side by side in such a manner as to bind somewhat during 40 their movement past each other into closed position, thus insuring their retention in that position.

It will be apparent from the foregoing that the frame may be readily adjusted to fit strops of appreciably different thicknesses, and that irrespective of its thickness, the strop will be prevented from swaying edgewise, due to the abutting engagement which exists between its end face and the top of the frame, or, more precisely, between its end face and the under face of the 45 lower flange 8. Also, it will be understood that any one of a number of different types of swivels may be interchangeably applied to the frame, according to the shape and size of the support from which the strop is to be suspended, and that the removal and 50 interchange of swivels may be quickly and easily effected.

I claim as my invention:

1. A swivel-carrying frame of **U**-section 60 adapted to be clamped to the upper end of a razor strop, comprising a pair of side plates having laterally-flanged upper ends which overlap each other and unite to form the base of the **U** and abut squarely against 65 the end face of the strop to hold the latter against rocking movement in the frame, said flanges being slidable transversely across each other to adjust the width of the frame to the thickness of the strop. 70

2. An adjustable frame for attachment to the upper end of a razor strop, comprising a pair of side plates having laterally-flanged upper ends which overlap each other and which have mating recesses therein that 75 unite to form a slot, said flanges being slidable transversely across each other to adjust the width of the frame to the thickness of the strop; in combination with a swivel 80 detachably connected to said frame and having a stem which is positioned in said slot.

3. A frame adapted to be attached to the upper end of a razor strop, comprising a member formed at its top with an open-ended recess, and a part movably related to 85 the frame member and having means for closing the open end of said recess; in combination with a swivel having its stem insertible into said recess through the open end thereof to permit the swivel to be detached from the frame. 90

4. A frame adapted to be attached to the upper end of a razor strop, comprising a pair of side plates having laterally-flanged upper ends which overlap each other and which are adapted to be adjusted transversely of each other to vary the width of the frame in accordance with the thickness of the strop, at least one of said flanges having a recess therein which opens through the 100 free edge of the flange and is closed at its open end by the flange on the other member; in combination with a swivel having its stem insertible into said recess through the open end thereof to permit the swivel to be detached from the frame. 105

5. A swivel-carrying frame attachable to the upper end of a razor strop and comprising a pair of side plates having flanged upper ends which overlap each other and are slidable transversely across each other to adjust the width of the frame to the thickness of the strop. 110

In testimony whereof I affix my signature.

DAVID S. WILLIAMS.
